TROUSERS

Harry C. D'Annunzio, Rochester, N. Y., assignor
to Fashion Park Manufacturing Corporation,
Rochester, N. Y., a corporation of New York

Application November 24, 1933, Serial No. 699,480

2 Claims. (Cl. 2—237)

My invention relates to an improvement in trousers and its novelty consists in the adaptation and arrangement of parts as will be more fully hereinafter pointed out.

5 During recent years clothes of a sporting type have become increasingly popular and trousers that eliminate the necessity for a belt or suspenders supply the requirement of this type of clothing. But it has been difficult to supply 10 this demand because the ordinary elastic member will not stand the necessary wear in the waist of a pair of trousers and also it is a real problem to insure the smooth fitting of such trousers. My trousers solve both of these serious 15 problems furnishing for the first time trousers that combine a waist elasticity that will stand the necessary wear and at the same time lie flat so as to effect a perfect fit.

Referring to the drawing Figure 1 is a rear 20 elevation of a pair of trousers embodying my invention with the lower ends broken away for convenience in illustration.

Figure 2 is the same as Figure 1 but with the 25 waist portion distended as in use.

Figure 3 is a front elevation of the trousers as shown in Figure 1.

Figure 4 is a portion of the waist section of the trousers on the line 4—4 of Figure 1.

In the drawing 5 is one side of the rear of my 30 trousers and 6 is the other side, which two sides 5 and 6 are joined together at the seam 7 in the usual well known manner. 8 and 9 are the usual 35 seams for fitting in the respective sides 5 and 6 and 10 and 11 are the usual type of hip pockets, the pocket 10 having the button 12 engaging 40 the usual buttonhole so as to button this pocket together in a secure closed position.

The trousers have outer waistband portions 13 45 and 14 each of which are cut and set in on the bias of the material, which material is the same as that in sections 5 and 6 of the trousers, and they are joined together at the usual seam 15. The upper edges of the rear trouser body elements 5 and 6 are shirred at 16 so that as they 50 are secured to the waistband portions 13 and 14 by the usual stitching at 17, said shirring 16 is stitched into position so that as the waistband elements 13 and 14 are stretched the shirring 16 will be taken up so as to effect the smooth 55 lying of the shirred portions 16 whereby both the waistband elements 13 and 14 and the shirred portions as well as the rest of the rear sections 5 and 6 will lie absolutely flat and smooth as clearly shown in Figure 2.

55 An internal elastic waistband 20 is adapted to

be folded back on itself as clearly shown in Figure 4 and its open edges stitched at 21 to the turned back upper edge of the outer waistband members 13 and 14. The middle portion of this elastic internal belt 20 is adapted to be stitched at 17' around its entire internal length to the point where the outer belt portions 13 and 14 are stitched to the lower body front portions 19 and 18 and the rear body portions 5 and 6. Thus we see that internal belt member 20, which is 10 adapted to be made of such a desirable elastic material as "Lastex", is so fastened and secured at 17' and 21 to the outer belt portions 13 and 14 that it will stretch with them as they are adapted to stretch because of their being cut on the bias 15 of the material of which they are made.

The front sections 18 and 19 of the trousers have the usual side pockets 22 and 23 and the overlapping outer belt member 13 has a button-hole 24 which buttons over button 25 secured 20 to the outer belt member 14 and there is the usual fly construction at 26, and 27 are heavy 25 plaits common to this type of sport trouser. 28 are the usual buttons used in fastening the fly 26.

It will thus be seen that the shirred elements 16 are only in the rear portions 5 and 6 of the trousers and will be so stretched as to flatten out and fit snugly and smoothly against the wearer in use as shown in Figure 2.

The inner elastic waistband member 20 is secured together at 29 at the rear forming the seam in absolute alignment with seam 7 of the rear trouser elements 5 and 6. This inner elastic belt member 20 running around the entire inner 35 face of the outer belt portions 13 and 14 will stretch in the front portion of the trousers joining the belt portions 13 and 14 above the front trouser elements 18 and 19 the same as it will with the rear portions of the outer belt elements 13 and 40 14, and said front portions of the outer belt elements 13 and 14 being cut and set in on the bias will stretch simultaneously with the said inner elastic belt member 20 so that there is a substantial stretching and smoothing out of the front 45 portion of the outer belt elements 13 and 14 with the inner elastic belt 20, but there will be a greater stretching of the rear portions of the outer belt elements 13 and 14 because of the shirrings 16 on the upper edges of the rear elements 5 and 6 50 of the trousers which permit a greater stretching of said outer belt elements 13 and 14 so as to insure the necessary complete stretching of the inner and outer belt portions 13, 14 and 20 of the 55

trousers to make them of practical utility in adapting themselves to fitting snugly on the wearer without the use of suspenders or belt.

It will be apparent that as the outer waistband 5 or belt elements 13 and 14 are made of the same cloth as the main body of the trousers although cut and set in on the bias, have a natural elasticity which will stand severe wear and use as well as body heat and perspiration without deterioration 10 common to the ordinary elastic elements in which rubber or one of its substitutes is used. Therefore the combined elements of the inner elastic waist or belt member 20 and the outer waist band members 13 and 14 will also have a much longer 15 life and function together than is possible with the single elastic element or other ordinary combinations.

It will be apparent that many variations may be made in the details of structure of my device 20 without departing from the spirit and intent of the same and that such variations fall within the purview of my invention.

I claim:

1. In a pair of trousers an elastic tight fitting waist portion comprising a waistband, the rear part of which is made of regular trouser fabric set in on the bias, the trousers being Shirred at 5 the upper edge in the rear and secured to the lower edge of the said bias waistband, and a second waistband of rubber material secured to the inner face of the bias waistband.

2. In a pair of trousers an elastic tight fitting 10 waist portion comprising a waistband which is made throughout of regular trouser fabric set in on the bias, the trousers being Shirred at the upper edge in the rear and secured to the lower edge of said bias waistband, and a second waist- 15 band of a rubber like material secured to the inner face of the bias waistband whereby the expansion and contraction of said waist portion is made possible.

HARRY C. D'ANNUNZIO. 20
